United States Patent Office

Des. 188,081
Patented May 31, 1960

188,081

BOAT

John Prince, Jr., Prairie Village, Kans., assignor to Pla-boat Marine, Inc., Independence, Mo., a corporation of Missouri

Filed Feb. 17, 1959, Ser. No. 54,651

Term of patent 3½ years

(Cl. D71—1)

Fig. 1 is a top plan view of a boat, showing my new design.

Fig. 2 is a bottom view thereof.

Fig. 3 is a side elevational view thereof.

Fig. 4 is a rear end view thereof; and

Fig. 5 is a cross-sectional view of a boat, taken on line 5—5 of Fig. 3.

I claim:

The ornamental design for a boat, as shown.
